UNITED STATES PATENT OFFICE

102,998

DESIGN FOR A SHOE CABINET

Frank O. Tashjian, Detroit, Mich.

Application November 16, 1936, Serial No. 65,944

Term of patent 3½ years

To all whom it may concern:

Be it known that I, Frank O. Tashjian, a citizen of the United States, residing at Detroit, in the county of Wayne and State of Michigan, have invented a new, original, and ornamental Design for Shoe Cabinets, of which the following is a specification, reference being had to the accompanying drawing, forming a part thereof,

The figure is a perspective view of a shoe cabinet, showing my new design.

I claim:

The ornamental design for a shoe cabinet, substantially as shown.

FRANK O. TASHJIAN.
